UNITED STATES PATENT OFFICE.

ELON A. MARSH, OF BATTLE CREEK, MICHIGAN.

VALVE FOR STEAM-PUMPS.

SPECIFICATION forming part of Letters Patent No. 394,656, dated December 18, 1888.

Application filed July 12, 1888. Serial No. 279,772. (No model.)

To all whom it may concern:

Be it known that I, ELON A. MARSH, a citizen of the United States, residing at Battle Creek, in the county of Calhoun and State of Michigan, have invented certain new and useful Improvements in Valves for Steam-Pumps; and I do hereby declare the following to be a full, clear, and exact description of the invention, such as will enable others skilled in the art to which it appertains to make and use the same.

My invention relates to improvements in steam-pumps, a principal object of the invention being to regulate the pressure of steam in the cylinder, so as to obtain isochronal movements of the pump and steam-piston under varying resistances, thus dispensing with the usual governor, in which the operation is always later than required for affording perfect control of the machine.

To this end my invention consists, generally, of the combination of a steam-engine valve and steam-ports constructed and arranged, as hereinafter described, to admit, cut off, or regulate the admission of steam to the cylinder, to increase or diminish the pressure therein through the medium of, and to correspond with the varying resistance to, the movement of the piston.

The details of the invention will be herein-after particularly described, and pointed out in the claims.

In the drawings, Figure 1 is a longitudinal vertical section through the steam-chest and steam and water cylinders, showing the air-chamber in elevation. Fig. 2 is a similar section through the exhaust and suction chamber, showing the steam-chest in elevation; and Fig. 3 is a sectional detail.

A is the main casting, in which the cylinders and chambers are formed, and to which the appendages are attached.

A' is the steam-cylinder, A'' the water-cylinder, N the exhaust-chamber, and M the suction-chamber, all preferably formed within the main casting A, as clearly appears in the drawings. Obviously these chambers may be formed of separate parts and then connected together without changing the character of my invention.

B is the steam-chest, mounted on the engine-cylinder in any usual or approved way and provided with live-steam passages G G' G'' G''', steam-ports F F', and enlarged end chambers, B' B''. The ports F F' are of less capacity than the annular ports a and a' and operate to restrict the incoming steam.

E is the live-steam pipe from the generator.

The steam-chest is provided also with a trip hole or passage in front of the plane of section of Fig. 1, (shown in dotted lines at b,) leading from the live-steam passages E' E'' to the steam-cylinder. It is also provided with trip-holes b' b'', leading from steam-cylinder to the valve-chambers B' B'', for a purpose hereinafter explained.

D D' is the steam or actuating valve of the engine, closely fitting the central bore of the steam-chest. This valve is reduced near the ends and along the middle, as shown, so as to admit steam through the annular ports a a' and to exhaust at a''. The valve is also provided with enlarged heads D'' D''', which fit the bore of the chambers B' B''. The area of the inside of these heads is reduced by the area of the reduced portions D D' of the valve.

C C' are the steam and water pistons, connected together and fitted to their respective cylinders A' and A''. The steam-piston is provided with a longitudinal channel or passage, c, having lateral holes c' c'', leading therefrom, which alternately register with the trip-holes b'' and b'.

J is a pin mounted in the main casting, projecting into a hole in the cylinder, to form a guide or stop to prevent the said cylinder from rotating, and thus insure the correct registry of the holes c' c'' with the trip-holes at each stroke of the piston.

H H are the cylinder-heads; I I, the steam-chest heads; T T, the cylinder-cocks; U, the air-cock; P, the water-suction pipe; P', the water-discharge pipe; L, the atmosphere-exhaust pipe; R, the air-chamber to the pump; O, a three-way valve or cock for making communication from exhaust-chamber N to atmosphere through L or from N to suction-chamber M; O', the valve-operating lever; Q and Q', pump-valves, and S a removable valve-seat.

Suitable stops are provided on the main casting to limit the movement of the valve-lever.

The operation of my invention is as follows:

5 The piston being in the position shown in Fig. 1 and steam admitted from live-steam pipe E, it first passes from E' through passage $b\ b'\ b''$ to enlarged chamber B'', and, acting on the head D''', drives the valve to the left and opens the annular port a'. When this is done, steam passes through annular port a' to the enlarged chamber B'', and thence through port F' and passage G to the main cylinder. The capacity of the port F' being less than that of port a' produces a stricture on the inflowing steam, and the pressure on the smaller inside surface of the head D''' becomes greater than against the larger outer surface, and thus moves the valve 10 to the right until it sufficiently restricts the annular port a' to produce the proper relative pressures on the outside and inside of the valve-head and to move the piston. When the piston C has moved far enough to uncover 15 the passage b'', the pressure in the chamber B'' will immediately rise and become uniform with that in the main cylinder. This increased pressure in the outer end of chamber B'' now exerts itself upon the larger area of 20 valve-head D''' and drives the valve to the left and enlarges the annular induction-port a'. As steam moves more rapidly than the piston, the pressure in the cylinder will be suddenly augmented, and this rise of pressure 25 operates still further to enlarge the induction-port; but when the pressure of steam in the cylinder becomes so great as to be out of proportion to the resistance the piston will race or rapidly recede before the preponderance of force and the pressure will become 30 reduced by reason of rapid expansion. This reduction of pressure in the cylinder and outer end of the chamber B'' enables the incoming steam to again move the valve to the 35 right until the forces on the two faces of the valve-head are neutralized. The valve thus automatically operated is the governor and regulator of the engine. The normal speed of the pump is fixed by the relative size of 40 the ports a' and the ports F F', the speed being greater when the stricture-ports F F' approach most nearly the capacity of the ports a a'. The stricture-ports are made so as to be reduced or enlarged at will by screw 45 cut-offs z z, or otherwise, as may be desired, so as to regulate the speed of the engine. The piston having moved to the left, so that the openings c' c'' register with the passages b b', a continuous passage, b c b', for 50 live steam from the pipe E to the outer end of chamber B' is made, and pressure on the outer surface of head D'' moves the valve to the right and reverses the current of steam. The annulus a'' of the valve now 55 couples the passage G G'' and exhaust takes place from the right of the cylinder through G G'' G''' to the exhaust-chamber N. The

piston is driven to the right until the passage c is again registered with the passages b b'', when the movement is again reversed, 70 and so on. When the water-plunger C moves from right to left, the air in the water-cylinder A'' is driven through the passage leading from water-cylinder to water-valve chamber, causing the water-valve Q' to leave its seat and allow the air to escape either through pipe P' or air-cock U. The valve then returns to its seat, and upon the return-stroke valve Q leaves its seat and air from suction-chamber M is admitted. When 80 the air is exhausted from chamber M and suction-pipe, water rises and fills the water-cylinder, and the machine will be in complete operation.

While the air is being exhausted the valve 85 O should be turned to open communication between exhaust-chamber N and pipe L, to permit the exhaust-steam to pass to atmosphere. After the pump has taken water, the valve O should be turned to the position 90 shown in the drawings to divert the exhaust-steam to suction-chamber M, where it is condensed and imparts its heat to the water—an important matter when used as a "feed-water."

Having now described my invention, I 95 claim—

1. In combination, a steam-chest provided with suitable ports, chambers and restricted passages from the chamber to the cylinder, and an actuating-valve having heads with 100 faces of unequal area, whereby said valve is operated to diminish or increase the flow of steam, and thereby regulate the pressure in the cylinder to correspond with the resistance to the piston or work to be done, substantially as described.

2. In combination, a steam-chest having restricted portage from valve-chamber to cylinder and an automatic valve having heads with faces of unequal area operating 110 to produce isochronism of the piston by equal and differential steam-pressure acting upon the unequal areas of the heads, the resistance of the piston serving to automatically regulate the pressure in the cylinder to correspond with the work required, substantially 115 as described.

3. In combination, an automatic valve for steam-engines, a trip-passage leading from live-steam passage to the engine-cylinder, similar passages leading from each end of said cylinder to the ends of the valve-chamber, and a longitudinal passage in the engine-piston, whereby the end passages from cylinder to the ends of valve-chamber are alternately coupled to the passage from live-steam pipe, and the valve is reversed by live-steam pressure, substantially as described.

4. An automatic valve for steam-engines, provided with exterior enlargements having 130 faces of different areas, in combination with induction-ports and restricting-ports, substantially as described.

5. The combination, with a steam-chest

having annular admission-ports and secondary restriction-ports, of a valve provided with heads having faces of unequal area, whereby the portage is restricted when the pressure in the engine is beyond that required to do the work, and said portage is increased when the pressure is insufficient, substantially as described.

In testimony whereof I affix my signature in presence of two witnesses.

ELON A. MARSH.
